United States Patent Office

Des. 218,150

Patented July 28, 1970

218,150

DISPENSING CONTAINER

Androus D. Noyes, Ossining, and Robert N. Marona,
Harrison, N.Y., assignors to Morton International, Inc.,
Chicago, Ill., a corporation of Delaware

Filed Dec. 30, 1968, Ser. No. 15,151

Term of patent 14 years

Int. Cl. D9—01

U.S. Cl. D9—118

FIG. 1 is a perspective view of a dispensing container showing our new design;

FIG. 2 is an elevational view on an enlarged scale;

FIG. 3 is an elevational view looking from the right of FIG. 2;

FIG. 4 is a top plan view of FIG. 3; and

FIG. 5 is a bottom plan view thereof.

We claim:

The ornamental design for a dispensing container, substantially as shown.
